UNITED STATES PATENT OFFICE.

GEORGE L. PARRISH, OF RICKETTS, PENNSYLVANIA.

TALKING-MACHINE-TOP SUPPORT AND RELEASE THEREFOR.

1,353,540.

Specification of Letters Patent. Patented Sept. 21, 1920.

Application filed May 29, 1920. Serial No. 385,351.

To all whom it may concern:

Be it known that I, GEORGE L. PARRISH, a blacksmith by trade, and a citizen of the United States, residing at Ricketts, in the county of Wyoming and State of Pennsylvania, have invented certain new and useful Improvements in Talking-Machine-Top Supports and Releases Therefor, of which the following is a specification, reference being had to the accompanying drawings.

This invention relates to the art of attachments for cabinet talking machines wherein closed cabinet tops or covers are employed and particularly to an improved top support and release therefor for supporting the cover or top in an open position.

An object is to provide a device of this kind including means for closing the cover or top readily with one hand of the operator by applying a slight pressure on an actuating rod in order to unlatch the support for the cover.

It has been found on various types of machines that it is necessary to employ two hands to lower the cover, one to engage the cover to hold it and steady it as it is liable to move downwardly to closed position and the other hand to actuate the support to permit the cover then to lower, therefore, an object is to avoid this inconvenience, and in accomplishing it it is the aim to provide a pivoted supporting latch so mounted relatively to the cover and a keeper on the cabinet that when the cover is raised to an open position, the supporting latch will automatically by gravitation move into engagement with the keeper, and support the cover in a raised position.

Another object is to provide a manually actuated member movable longitudinally to release the supporting latch from engagement with the keeper, whereby the cover may easily lower, the use of only one hand of the operator being necessary to actuate the longitudinally movable member.

Still another object is the provision of a swivel connection between the longitudinally movable member and a device carried by the latch, whereby the latch may be actuated so that the latch may be disengaged from its keeper.

While the design and construction at present illustrated and set forth is deemed preferable, it is obvious that as a result of a reduction of the invention to a more practical form for commercial purposes, the invention

may be susceptible to changes, and the right to these changes is claimed, provided they are comprehended within the scope of what is claimed.

The invention comprises further features and combination of parts, as will be herein-after set forth, shown in the drawings and claimed.

In the drawings:

Figure 1 is a perspective view of a cabinet talking machine including a cabinet cover, showing the improved cover supporting latch and release therefor as applied, and constructed in accordance with the invention,

Fig. 2 is an enlarged detail perspective view of the supporting latch; and

Fig. 3 is a sectional view on line 3—3 of Fig. 2.

Referring to the drawings, 1 designates a conventional form of cabinet talking machine, and 2 denotes a plate which is secured to the top of the cabinet body as by means of screws 3. This plate constitutes a keeper and is provided with an elongated slot 4.

Secured to the cover or the hinged top of the machine as by means of the screws 5 is an angle plate 6, to which a supporting latch 7 is pivotally connected as at 8. The lower part of this supporting latch passes through the slot 4 of the keeper plate and is provided with a notch 9. It is to be noted that the angle plate 6 is so disposed relatively to the keeper plate when the cover is closed or opened that when the cover is open, the supporting latch will automatically by gravitation move so that the notch 9 will engage the marginal edge of one end of the slot 4 in the keeper plate, thereby preventing downward movement of the cover or hinged top. Heretofore it is necessary to use one hand to engage the cover and the other hand to release the supporting latch when it is desired to lower the cover.

The present invention aims to avoid such inconvenience by providing an actuation member for the supporting latch so that when the member is moved, while the same is still grasped in the hand of the operator, the cover may be steadied as it is lowered, and in this way accomplishing the lowering of the cover with the use of one hand instead of two. In order to attain this result, a U-shaped clevis 10 is arranged to straddle the supporting latch 7 transversely, that is

to say, from the edge thereof. A set screw 11 is carried by one arm of the U-shaped clevis and engages the supporting latch as at 12 so as to hold the clevis in different adjusted positions on the supporting latch.

- One arm of the clevis has an upstanding ear or lug 13 to which a coupling block 14 is swivelly or pivotally connected as at 15. In other words, this coupling block has a lateral pivot pin 15 which engages through the ear or lug 13 and is swaged as at 16 to form a head, thereby pivotally or swivelly connecting the coupling block to the ear. This coupling block has an opening 17. Mounted on one edge of the cover of the talking machine is a guide eye 18 in which an actuating rod 19 is guided. One end of this rod terminates in a ring or eye 20, which extends downwardly and laterally from the side of the cover so that it may be easily grasped by one hand of the operator. The other end portion of the rod 19 passes through the opening 17 of the coupling block, and is engaged by a set screw 20^a, which is threaded through one side of the coupling block, thereby adjustably connecting the coupling block on the rod.

As before stated, the angle plate 6 is so disposed relatively to the keeper plate that when the cover is raised the notch of the supporting latch will automatically engage one end of the slot of the keeper plate. With the present invention as applied in the manner shown and set forth, a pull upon the rod 19 will move the supporting latch pivotally in a direction of the front of the cabinet of the machine, thereby disengaging the notch from the keeper plate. The rod 19 is still maintained in a forward position, and the hand of the operator still remains in engagement with the ring or eye 20 so as to steady and hold the cover as it is moving to a closed position, thereby preventing the cover from falling with force and thereby avoiding the use of two hands to lower the cover.

The invention having been set forth, what is claimed as new and useful is:—

1. In a cabinet, the combination with a body, of a hinged cover therefor, a pivoted supporting latch carried by the cover, a

keeper secured to the body to be engaged by the supporting latch, a clevis adjustably and detachably connected to the supporting latch, a coupling block operatively and pivotally mounted on the clevis, and a longitudinally movable member mounted in guides of the cover and being in turn adjustably connected to the coupling block, whereby upon imparting a movement to the longitudinal movable member, the supporting latch may be disengaged from its keeper.

2. In a cabinet, a cabinet body, a cover hingedly mounted thereon, a keeper plate having a slot carried by the top of the cabinet body, a supporting latch pivotally mounted on the cover, said supporting latch being positioned on the cover relatively to the keeper, whereby when the cover is raised to an open position, the supporting latch will automatically by gravitation engage one end of the slot of the keeper, a clevis carried by the supporting latch, a coupling block pivotally and operatively mounted upon the clevis, a longitudinally movable member mounted in a guide of the cover and being adjustably connected to the coupling block, whereby upon moving the member, the supporting latch may be disengaged from the keeper.

3. In a cabinet, a cabinet body having on its upper surface a keeper plate provided with an elongated slot, a cover hinged thereto, a supporting latch so pivotally mounted upon the cover relatively to the keeper plate and provided with a notch, whereby upon raising the cover to an open position, the supporting latch will gravitate, whereby the notch may engage one end of the slot in the keeper plate, a clevis adjustably fixed on the supporting latch, a coupling block pivoted on the clevis, a longitudinally movable member mounted in a guide of the cover and being in turn adjustably connected to the coupling block, whereby upon moving the member in a direction forwardly of the cover, the supporting latch may be disengaged from the keeper.

In testimony whereof I hereunto affix my signature.

GEORGE L. PARRISH.
